Primary Examiner — T Chase Nelson*Assistant Examiner* — Kelly L Gross(74) *Attorney, Agent, or Firm* — Liang & Hennessey LLP; Stanley D. Liang(57) **CLAIM**

The ornamental design for an infusion bag, as shown and described.

DESCRIPTION

The sole FIGURE is a front view of an infusion bag showing our new design.

The broken lines on the FIGURE showing wording, symbols, barcodes, and boxes are environment only and form no part of the claimed design.

1 Claim, 1 Drawing Sheet(56)
